UNITED STATES PATENT OFFICE.

WILLIAM G. STEWART, OF WINDSOR, ONTARIO, CANADA.

ACCELERATOR ATTACHMENT.

Application filed June 18, 1921. Serial No. 478,639.

To all whom it may concern:

Be it known that I, WILLIAM G. STEWART, a subject of the King of Great Britain and Ireland, residing at Windsor, in the Province of Ontario and Dominion of Canada, have invented certain new and useful Improvements in Accelerator Attachments, of which the following is a specification, reference being had therein to the accompanying drawings.

The invention relates to accelerators for use on motor cars and consists in a pneumatically actuated construction which is applicable either to cars unprovided with foot accelerators or to cars having accelerators where a more convenient location of the actuating means is desired. For instance, a location of accelerator suitable for one operator may be very inconvenient for another operator and also in long continued driving it is restful for the operator to change the position of his foot. Therefore, my improvement may be advantageously used on any type of motor car. I have, however, specifically shown it as applied to a car of the Ford type.

In the drawings:

Figure 1 is a diagrammatic plan view of the attachment as installed;

Figure 2 is a perspective view; and

Figure 3 is a cross-section through the pneumatic bulb.

Certain makes of motor cars, as, for instance, the Ford, are unprovided with foot-operated accelerators. They have, however, a hand-operated control for opening and closing the throttle, which includes a pair of rock arms and a connecting rod or link. My improvement consists in a pneumatically operated device, including a foot-actuated compressor bulb and an expansion chamber operated thereby. Also, a substitute connecting rod having slidably engaged portions between which said expansion chamber is arranged.

In detail, A is the steering column of a motor car and B the rock shaft adjacent to said column, which is actuated by the hand control and which is provided at its lower end with a rock arm C having a rod connection with a rock arm D of the throttle. My attachment consists in a substitute rod E having at one end the bent arm F and at its opposite end an arm G, preferably adjustably connected by a threaded engagement with the rod, as indicated at H.

Upon the rod E is sleeved a member I, preferably of U-shaped form, having an arm portion J extending parallel to the bent arm F and two apertured bearings which 60 slidably engage the rod. The member I is pivotally attached to the end of the rock arm C, while the member G pivotally engages the rock arm D. L is a compressor bulb formed of rubber or other suitable material and which is connected by a tubing M with an expandible chamber N, preferably a pair of peripherally attached disks. The member N is placed between the arm J and the bent arm F and the opposite sides of 65 the disks are preferably engaged with said arms, as by means of stirrups O.

With the device as described, whenever pressure is placed on the bulb L, the compressed air passing through the tube M will 70 expand the disks and force the arms F and J apart from each other. As the arm J is held by the rock arm C of the hand control, the effect of expansion of the member N is removed from the rod E relative thereto, 75 thereby rocking the throttle arm D. When the pressure on the bulb L is released, the expansion of said bulb will collapse the member N, drawing the arms F and J towards 80 each other and actuating the throttle arm D in the reverse direction. To render this action more positive, the bulb 85 L has the pressure therein normally reduced below atmosphere. To accomplish this, the bulb L is preferably provided with an opening L' which is normally closed by means of a spring-pressed valve P. This valve may be moved inwardly against the tension of its spring to permit the air in the bulb to escape when the latter is partly compressed and then may be closed by its spring to prevent ingress of air when the bulb is 90 expanded. This, by reducing the pressure within the member L will permit external atmospheric pressure to positively actuate 95 the arms F and J towards each other. If desired, a spring Q may be sleeved upon the rod E between a collar R thereon and the member I to operate in conjunction with the expansion of the bulb L in returning 100 the throttle. This constitutes a safety device in case the pneumatic mechanism should fail to operate.

The device constructed as described can be manufactured at very low cost and any user of a motor car can quickly install it. The bulb L may rest upon the floor of the

car in any convenient position. Thus, the operator can accelerate by a foot in much the same manner as on standard motor cars having foot accelerators.

5. Where my accelerator is placed upon a different type of car, some modifications may be required in the specific construction, but in general the construction is the same.

One advantage of a pneumatically operated accelerator is the non-positive resiliency of the same. With mechanically actuated accelerators it frequently happens, when driving over a rough road, that it is difficult to operate the motor smoothly.

15. This is because any vibration of the foot will be positively transmitted to the throttle but with my pneumatic construction such vibrations will have no effect on the throttle. In other words, the resiliency of the air 20 will compensate for quick vibrations.

What I claim as my invention is:

1. An accelerator attachment for motor cars comprising a substitute connecting rod between the hand control and throttle, having members relatively movable longitudinally of the rod, a pneumatic compressor bulb and an expansible chamber connected with said bulb engaging said relatively movable members of the rod to actuate the same.

30. 2. An accelerator attachment for motor cars comprising a substitute connecting rod between the hand control and throttle, including slidably engaged members having adjacent laterally extending arms, a pneumatic compressor bulb, and an expansible chamber connected with said bulb inserted between said arms to relatively move the same.

35. 3. An accelerator attachment for motor cars comprising a rod between the hand control and throttle formed in relatively movable sections having laterally projecting arms adjacent to each other, a pneumatic compressor bulb, an expansible chamber connected therewith and inserted between said adjacent arms and secured thereto, the air within said bulb when said pressure is expanded being at less than atmospheric pressure, whereby said arms are 50 drawn together by atmospheric pressure.

40. 4. An accelerator for motor cars comprising a pneumatic compressor bulb, the pressure in said bulb normally being reduced below atmospheric pressure, an expansible chamber located to actuate the throttle, and a flexible connection between said bulb and expansible member, whereby said bulb may 55 be moved from one position to another.

5. An accelerator attachment for motor cars comprising a substitute connecting rod 60 between the hand control and throttle, having relatively movable members, a pneumatic compressor bulb, and expansible means connected to said bulb and disposed between said members for moving the same. 65

6. The combination with an accelerator mechanism for a motor vehicle, of pneumatic means connected to said mechanism for actuating the same comprising an expansible member and a bulb connected to 70 said expansible member and adapted to be compressed to expand the same, the pressure in said bulb normally being below atmospheric pressure whereby said expansible member will be contracted by atmospheric 75 pressure to return said accelerator mechanism to normal position when said bulb is expanded.

7. The combination with an accelerator mechanism for a motor vehicle, of pneumatic means connected to said mechanism for actuating the same comprising an expansible member and a bulb connected to 80 said expansible member and adapted to be compressed to expand the same, the pressure in said bulb normally being below atmospheric pressure whereby said expansible member will be contracted by atmospheric 85 pressure to return said accelerator mechanism to normal position when said bulb is expanded, and means adapted to return said accelerator mechanism to normal position upon failure of said expansible member to operate.

8. The combination with accelerator 95 mechanism for a motor vehicle, of foot-operated compressor means, and fluid transmission means between said compressor means and accelerator mechanism.

9. The combination with accelerator 100 mechanism for a motor vehicle, of foot-operated compressor means freely shiftable to different operating locations, and a connection between said compressor means and mechanism permitting such shifting movement.

10. The combination with accelerator mechanism for a motor vehicle, of foot-operated compressor means freely shiftable to different operating locations and producing in its operation no reaction tending to shift its location, and a flexible fluid transmission means between said compressor and said mechanism.

In testimony whereof I affix my signature.
WILLIAM G. STEWART.
